UNITED STATES PATENT OFFICE

134,250

DESIGN FOR A COMBINED LIPSTICK AND HOLDER

Martin de Botelho, New York, N. Y.

Application November 12, 1941, Serial No. 104,118

Term of patent 7 years

To all whom it may concern:

Be it known that I, Martin de Botelho, a citizen of Brazil, residing in the city, county, and State of New York, have invented a new, original, and ornamental Design for a Combined Lipstick and Holder, of which the following is a specification, reference being had to the accompanying drawing, forming a part thereof, in which:

Fig. 1 is a side elevational view of a combined lipstick and holder in closed position, showing my new design;

Fig. 2 is a top plan view thereof; and

Fig. 3 is a perspective view of the base in upright position with the cover member lying on its side to show the interior thereof.

The characterizing features of my design for the combined lipstick and holder reside in the configurations and proportions of parts of the base portion thereof as best shown in Fig. 3 of the drawing.

I claim:

The ornamental design for a combined lipstick and holder, substantially as shown and described.

MARTIN DE BOTELHO.
